UNITED STATES PATENT OFFICE.

WILLIAM C. STARKEY, OF MANSFIELD, OHIO, ASSIGNOR TO THE OHIO BRASS COMPANY,
OF MANSFIELD, OHIO, A CORPORATION OF NEW JERSEY.

SUSPENSION DEVICE.

1,402,023.

Specification of Letters Patent. Patented Jan. 3, 1922.

Application filed July 28, 1921. Serial No. 488,235.

To all whom it may concern:

Be it known that I, WILLIAM C. STARKEY, a citizen of the United States of America, residing at Mansfield, in the county of Rich-
5 land and State of Ohio, have invented cer-
tain new and useful Improvements in Sus-
pension Devices, of which the following is
a specification.

My invention relates to a device for en-
10 gaging and supporting a conductor and more
particularly to that class of conductors
known as trolley wires or trolley conductors.

My invention has for its object a device
which can be made to quickly grip or en-
15 gage the trolley wire through the medium
of a cam action and in the particular form
of device shown and described the grip
comprises a duplex engagement in that there
are two cams, one for directly engaging the
20 conductor and the other for forcing a mem-
ber into engagement with the conductor.
There are also means on the device for con-
necting supporting or anchor cables.

These and other new and useful objects
25 as will appear later are secured and attained
by the novel construction, combination and
arrangement of parts of which my invention
is composed and which will appear later,
as more fully described and claimed and
30 shown in the accompanying drawing in
which:—

Fig. 1 is a side elevation of my device as-
sembled with conductor in place and showing
35 one of the cam engaging members out of
operative engagement with the conductor and
clamping plate.

Fig. 2 is an end elevation of Fig. 1.

Fig. 3 is a top assembled view of my de-
vice.

40 Fig. 4 is a sectional view on the line 4—4
of Fig. 3. My preferred construction shown
and described comprises three members,
namely—a body member 1 provided with
hook lugs 2 at each end and a longitudinal
45 U-shaped groove to receive the conductor
and having the lugs at the ends oppositely
disposed with respect to the U groove; a
clamping member having a horizontal portion
50 4 and provided with a member 5 adapted
to enter the longitudinal U-shaped groove
3 and engage with the trolley wire 6 or

conductor and also having eyes 7 for the
reception of a supporting, strain, anchor
cable and the like; and a pair of cam tips
8 each provided with lips 9 at one end to 55
engage and be formed about the conductor.
The cam tips are also provided with two
cam members 10 and 11 and the cam mem-
ber 10 is connected to the tip by means of
a shaft like construction 12. The shaft mem- 60
ber 12 is adapted to engage with the hook
members 2 and rotate relatively to the hook
members.

The cam 10 is so arranged that it will
engage the horizontal portion 4 of the 65
clamping member and the cam 11 is so
arranged as to engage the conductor when
the device is properly installed upon the
conductor. The parts before assembly are
all separable.

70 In order to install the invention the parts
are first disassembled. The U shaped body
member 1 is then placed in position with the
conductor resting in the longitudinal groove.
The plate 3 is then placed in position with 75
the member 5 in engagement with the trolley
wire 6. One of the cam members 8 is then
placed in position with the member 12 en-
gaging the interior of the hook member 2
and as shown in the dotted line construction 80
in Fig. 1 and the cam member is then ro-
tated down into final position and in this op-
eration of rotation the cam 10 engages the
clamping member 4 and the cam 11 engages
85 the conductor forcing the clamping member
4 and conductor simultaneously into position.
This operation with the cam member is re-
peated with the other cam or both cam mem-
bers may be operated into position sim-
90 ultaneously. This forms a secure clamp upon
the trolley wire and after such installation
as described the lips of the member 9 can
then be peened or formed about the con-
ductor, thereby locking the device as against
95 disassembly. If desired, supporting, strain
or anchor cables may be secured in the eye
members 7.

Having shown and described my inven-
tion I do not wish to be limited to the ex-
act construction shown and described, as 100
there are variations which can be made and
which will be readily recognized by one

skilled in the art and which will come within the scope of my invention as set forth in the following claims:—

1. A trolley device comprising a body member provided with a receiving means for a conductor, a holding member arranged to cooperate with the body member and having means to engage the conductor and having means to receive supporting means, retaining means on the body member, and a rotatable member to engage the retaining means, the holding member, and the conductor whereby the parts are moved into secure relation with each other when the rotatable member is moved into position, the rotatable member having also means to grip the conductor beyond the body member after the parts are in final position.
2. A trolley device comprising a body member provided with a receiving means for a conductor, a holding member arranged to cooperate with the body member and having means to engage the conductor and having means to receive supporting means, retaining means on the body member, and a rotatable member to engage the retaining means, the holding members, and the conductor whereby the parts are moved into secure relation with each other when the rotatable member is moved into position.
3. A trolley device comprising a body member provided with receiving means for a conductor, a holding member arranged to cooperate with the body member and having means to engage the conductor, retaining means on the body member, and a rotatable member to engage the retaining means, the holding member and the conductor whereby the parts are moved into secure relation with each other when the rotatable member is moved into position.
4. A trolley device comprising a body member provided with a receiving means for a conductor, a holding member arranged to cooperate with the body member and having means to engage the conductor and having means to receive supporting means, retaining means on the body member, and a rotatable member to engage the retaining means, the holding member and the conductor whereby the parts are moved into secure relation with each other when the rotatable member is moved into position.
5. A trolley device comprising a body member provided with a receiving means for a conductor, a holding member arranged to cooperate with the body member and having means to engage the conductor, retaining means on the body member, and a member to engage the retaining means, the holding means and the conductor, and having means to simultaneously move all parts into secure relation with each other.
6. A trolley device comprising a body

member provided with a receiving means for a conductor, a holding member arranged to cooperate with the body member, and having means to engage the conductor, retaining means on the body member, and a member to engage the retaining means, the holding means and the conductor, and having means whereby the parts are moved into secure relation with each other.

7. A trolley device comprising a body member provided with means to receive a conductor, a holding member arranged to cooperate with the body member, and having means to engage the conductor, retaining means at each end of the body member, and a rotatable member cooperating with the retaining means, and provided with cam means to engage and force the holding member into position when rotated.

8. A trolley device comprising a body member provided with a receiving means for a conductor, a holding member arranged to cooperate with the body member, and having means to engage the conductor, retaining means on the body member, and a member having means to cooperate with the retaining means and having means to engage and force the holding member into position.

9. A trolley device comprising a body member provided with a receiving means for a conductor, a holding member arranged to cooperate with the body member, and having means for attachment to supporting means, retaining means on the body member, and a member having means to cooperate with the retaining means, and having means to engage and force the conductor into position, and means to engage and force the holding member into position.

10. A trolley device comprising a vertically disposed body member provided with means to receive a conductor, a holding member arranged to cooperate with the body member as and for the purpose described, a retaining means on the body member, and a member to cooperate with the retaining means and rotate in a vertical and longitudinally disposed plane and having means to engage the conductor and the holding member to move them into final position and relation.

11. A trolley wire device comprising a vertically disposed body member provided with a groove to receive a conductor, a horizontally disposed holding member provided with projecting means to enter the groove and cooperate therewith to engage and clamp a conductor, and having supporting means; a hook-shaped retaining means at each end of the body member and a rotatable member co-operating with the retaining means, and provided with cam acting means to engage and force the conductor into position and provided with cam means

to engage and force the holding member with the retaining means, and provided with into position, and also provided with means a cam member and means interposed between the cam member and the conductor 10 to engage and hold onto the conductor.

12. A trolley device comprising a body member provided with a receiving means for a conductor, retaining means on the body member, a rotatable member to cooperate with the retaining means, and provided with a cam member and means interposed between the cam member and the conductor 10 and engaging the conductor when the rotatable member is moved into final position.

WILLIAM C. STARKEY.
